Frank D. Thomason

UNITED STATES PATENT OFFICE.

CHARLES A. TAYLOR, OF CHICAGO, ILLINOIS, ASSIGNOR TO JOHN H. SESSIONS, OF BRISTOL, CONNECTICUT.

TRUNK-FIXTURE.

SPECIFICATION forming part of Letters Patent No. 389,119, dated September 4, 1888.

Application filed March 5, 1888. Serial No. 266,276. (No model.)

To all whom it may concern:

Be it known that I, CHARLES A. TAYLOR, of Chicago, in the county of Cook and State of Illinois, have invented certain new and useful 5 Improvements in Trunk-Fixtures, of which the following is a full, clear, and exact description, reference being had to the accompanying drawings, and to the letters of reference marked thereon.

10 The object of my invention is to provide a simple and economical fixture for trunk-trays, whereby said tray can be closed into the lid of the trunk and maintained there when the lid is open, and which automatically releases 15 said tray when the lid of the trunk is closed onto the body thereof, substantially as herein-after fully described, and as illustrated in the drawings, in which—

Figure 1 shows a transverse vertical section 20 of the top of a trunk in which the tray is located, showing my improvements applied thereto. Fig. 2 is a front view of my improved fixture. Fig. 3 is a side elevation thereof, and Figs. 4 and 5 show side views of modifications 25 of the same.

Referring to the drawings, A represents the body of a trunk, B the lid thereof, and C the tray, set within said trunk, resting on cleats or ledges in the body of the same, hinged in the 30 usual manner at the rear to the upper edge of said body, and of such height that its upper half is within the lid when the trunk is closed.

The front horizontal edges of the bodies of trunks are generally re-enforced by placing a 35 longitudinal strip, *a*, along the inner surface thereof flush with and parallel to said edge, and the front surface of trays that arise above the horizontal plane of the upper edges of the bodies of the trunks are beveled from the up- 40 per edge and the lower edge toward and to the horizontal line intersected by and on the same plane as the upper edges of the bodies. This beveling is intended to facilitate the opening or swinging of the tray up out of the body and 45 toward or into the lid of a trunk. This common construction affords me the opportunity of using the spring D, which consists, preferably, of a strip of flat spring metal of a length less than the height of the tray and provided 50 with a suitable hole, *b*, in its upper half and with a horizontal slot, *c*, preferably midway

between its side edges above said hole *b* and near the upper end of said spring D. This spring is bent and curved outward, so that its normal shape in profile is substantially that 55 shown in Fig. 3, and it is secured vertically, preferably at about the center of length, to the tray, so that one half is above and the other below the vertex of the double bevel of the front surface thereof. It (the spring) is secured at its lower end to said tray by suitable means, and its upper end is held to the same by a suitable nail, screw, or rivet, *d*, which passes through slot *c*, and the head of which is greater in diameter than the width of said slot. 65

When a tray with my improved spring D is closed into the body of a trunk, the said spring is depressed against the tray by striking and moving down past the re-enforcing strip *a*. This depressing of the spring or straightening 70 out of its normal curvature causes its upper end to move vertically toward the upper edge of the tray. This vertical movement is accommodated by the slot *c*. When, however, the tray is lifted, or, rather, oscillated, out of the 75 body of the trunk, the said spring bulges outward, as shown in Fig. 3, and when closed into the lid of the trunk is caught by the lug *e*, secured to and projecting in from the inner surface of said lid, slipping into said hole *b*, thus 80 preventing the tray from falling out of said lid while the same is open. By pressing the spring inward, or by closing the lid down upon the body of the trunk, said spring is moved off of the lug *e*, and thus releases the said tray from 85 said lid.

Instead of making the slot *c* in the said spring, its upper end could be placed through and moved in a suitable staple projecting from the tray. 90

Fig. 4 shows a modification of my improved spring-fixture, and consists, briefly speaking, of a suitably-curved wire spring, E, which, instead of being secured to the front of the tray, is secured to the side thereof contiguous to the 95 front surface, so that its curved length bulges out past the plane of the front surface and is provided with a shoulder or offset, *f*, which, when closed into the lid, snaps into a suitable recess made in register therewith in the inner 100 surface thereof.

Fig. 5 is substantially the same as the modi-

fications shown in Fig. 4, except that, instead of being made of wire, it is made of cast metal, the upper end of the casting E being forced outward by the constant pressure of a spring, 5 and the curved extension *g* having a shoulder which snaps into a suitable recess the same as does the wire extension of the device shown in Fig. 4 when closed into the lid.

What I claim is—

- 10 1. The combination, with the body of a trunk having strip *a* secured against the inner surface of the front upper edge thereof and a lid, of a tray resting within and hinged at the rear to said body and arising into the lid of said 15 trunk, and a spring having a shoulder formed therein secured to said tray, which catches upon shoulder of the lid when the same is open, and which automatically releases itself from said lid when oscillated into said body 20 part of the trunk.
2. The combination, with the body of a trunk having a strip, *a*, secured to the upper inner

edge, the lid thereof, and a lug, *e*, secured and projecting from its inner surface, of a tray hinged at the rear to said body and a flat 25 spring secured to the front of said tray and having an opening, *b*, with which lug *e* engages therein, as set forth.

3. The combination, with the body of a trunk having a projecting strip secured parallel to 30 and against the inner front upper edge thereof, the lid of the same, and a lug, *e*, secured to and projecting from the inner surface of the front of the same, of the tray hinged at the rear to said body, a spring, *D*, secured to the front of 35 said tray, so as to engage in vertical register with said lug, having an opening, *b*, and a slot, *c*, and a rivet, *d*, as and for the purpose set forth.

CHARLES A. TAYLOR.
